CLAIM

The design for an electronic grade rod, as shown and described.

DESCRIPTION

The present application claims priority from U.S. patent application Ser. No. 17/089,574, filed on Nov. 4, 2020, which is a continuation-in-part patent application of U.S. patent application Ser. No. 15/627,340, filed on Jun. 19, 2017, which is a regular application of U.S. Provisional Patent Application 62/351,676, filed on Jun. 17, 2016, whereby each of the listed patent applications is incorporated herein by reference in their entirety.

FIG. 1 is a top front perspective view of an electronic grade rod.

FIG. 2 is a top rear perspective view thereof.

FIG. 3 is a front view thereof.

FIG. 4 is a first side view thereof.

FIG. 5 is a rear view thereof.

FIG. 6 is a second side view thereof.

FIG. 7 is a top view thereof.

FIG. 8 is a bottom view thereof.

FIG. 9 is a second front view thereof; and,

FIG. 10 is an enlarged front view thereof.

The broken line showing is included for the purpose of illustrating portions of the “article” and forms no part of the claimed design.
